UNITED STATES PATENT OFFICE.

JOHN F. HEMENWAY, OF NEW YORK, N. Y.

PRESSURE-ROLL RELEASE FOR CLOTHES-WRINGERS.

1,211,702.

Specification of Letters Patent. Patented Jan. 9, 1917.

Application filed July 12, 1916. Serial No. 108,909.

To all whom it may concern:

Be it known that I, JOHN F. HEMENWAY, a citizen of the United States, residing at New York city, in the county of New York and State of New York, have invented certain new and useful Improvements in Pressure-Roll Releases for Clothes-Wringers, of which the following is a specification, reference being had therein to the accompanying drawing.

This invention relates to certain new and useful improvements in pressure roll release for clothes wringers, and is an improvement upon my pressure release as covered in an application filed by me March 31st, 1916, Serial No. 88,009, the object being to provide a pressure release in which the top bar of the wringer frame carrying the pressure screws can be released in order to allow the same to move vertically a predetermined distance in order to release the pressure on the pressure rolls without detaching the top bar from the wringer frame.

Another object of my invention is to provide a pressure roll release which is mounted on the under side of the top bar in such a manner that the same is out of the way, said release being in the nature of a flat spring having substantial T-shaped ends coöoperating with slotted members carried by the side bars of the frame.

Another and further object of the invention is to provide the top bar with an operating member in the form of a push button which is adapted to be forced downwardly in order to draw the reduced ends of the springs in alinement with the reduced slots of the members carried by the side bars so as to allow the top bar to move vertically.

Other and further objects and advantages of the invention will be hereinafter set forth and the novel features thereof defined by the appended claims.

In the drawings, Fig. 1 is a front elevation partly in section of a clothes wringer showing the application of my improved construction of pressure release thereto, Fig. 2 is a section taken on the line 2—2 of Fig. 1 showing the position of the spring on the under face of the top bar. Fig. 3 is an end view showing the spring in position within the slot of the member carried by the side bars of the frame, and Fig. 4 is a detail

perspective view of the spring and member carried by the side bar.

55

Like numerals of reference refer to like parts in the several figures of the drawing.

In the application of my improved construction of pressure release for clothes wringers, I show a clothes wringer comprising a frame 1 composed of slotted side bars 2 connected together at their lower ends by a rod 3 and connecting members 4, and at their upper ends by a movably mounted top bar 5. Mounted in the slotted side bars 6 of the wringer frame are bearings 6 and 7 in which the shafts 8 and 9 of the pressure rolls 10 and 11 are mounted, the shaft 8 extends outwardly beyond the wringer frame and is adapted to be driven by any suitable means such as a pulley or crank.

The shafts 8 and 9 carry meshing gears, not shown, at each end of the pressure rolls which are inclosed by gear casings 11'. The upper bearings 7 are provided with 75 spring supports 8' on which are mounted the lower ends of the coil pressure springs 12 carrying a pressure bar 13 which is preferably provided with plates 14 at its ends having depending studs fitting within the top of the springs, said plates forming bearings for the lower ends of pressure screws as will be hereinafter fully described. The top bar 5 of the wringer frame is provided with a pressure screw 15 at each end, and the 85 lower end is mounted on the plates 14 carried by the pressure bar 13 so as to exert a pressure upon the bearings of the upper pressure rolls through the medium of the pressure springs.

90
The above description is given so that the application of my improved release for this form of wringer can be clearly understood, but of course, my improved releasing device is capable of being attached to any of 95 the well known wringers now in use in which a movably mounted top bar is employed for carrying the pressure screws.

Secured to the upper end of each of the side bars 2 of the wringer frame is a member 16 which bridges the slotted portion thereof and is provided with a horizontally disposed slot 17 communicating with a vertically disposed slot 18 forming a substantially inverted T-shaped opening in the 105 member, the slot 17 being of a greater width

than the slot 18, for the purpose herein-after fully described.

Slidably mounted on the under side of the top bar 5 is a flat spring 19 herein shown provided with slots 20 through which headed screws 21 pass for holding the same in position on the under face of the top bar 5 in such a manner that the spring 19 is free to move thereon, and while I have shown the spring 19 slotted and mounted on the top bar 5 in this particular manner, I do not wish to limit myself to any particular manner of mounting the same, as various other means can be employed for slidably supporting the spring on the under face of the top bar without departing from the spirit of my invention.

The spring 19 is provided with slotted portions in alignment with the pressure screws 15 of the top bar 5 through which the pressure screws 15 pass and engage the bearing plates 14 of the pressure bar 13 as clearly shown in Fig. 1 so as to allow the spring 19 to expand and contract. The ends 25 of the spring 19 are provided with substantially T-shaped heads 22 formed by providing the spring with oppositely disposed notches to provide reduced portions 23 which are of a width substantially the same as the width of the slot 18 in order to allow the top bar to move vertically when the reduced portion of the spring are brought into alignment with the slots 18 of the members 16.

35. In order to provide means for depressing the central portion of the spring in order to draw the reduced portions of the ends of the spring into alignment with the slots 18, I provide the top bar with a vertical bore 24 having an enlarged portion 25 in its under face in which is arranged a nut 26 having a rounded lower face which is carried by the threaded lower end 27 of a push button 28, slidably mounted within the bore 24 of the top bar 5, said nut being locked upon the push button by a lock washer 29 as clearly shown in Fig. 1 in order to prevent the nut from rotating on the push button after the same has been adjusted in position 45 thereon.

The operation of the pressure release as herein shown and described is as follows: Assuming that the top bar is in the position as shown in Fig. 1 of the wringer frame the 55 portions of the spring adjacent the reduced portions in the horizontally disposed slots 17 of the members 16 so as to hold the top bar 5 rigidly in position within the slotted portions of the side bars of the frames so that the pressure screws can be operated to exert the proper pressure on the pressure means of the wringer. In case of an accident, or a foreign object being drawn between the pressure rolls and it is desired to 60 release the pressure means instantaneously,

it is only necessary for the operator to strike the push button 28 which is provided with an enlarged head so as to force the nut into engagement with the flat spring which bores the central portion thereof in order to draw the ends of the spring inwardly which brings the reduced portions 23 into alignment with the vertical slots 18 of the members 16, and allows the top bar to move a predetermined distance within the wringer frame which releases the pressure on the pressure rolls. As the top bar of the same moves vertically within the wringer frame, the heads formed on the ends of the flat spring 19 prevent the spring from being drawn inwardly to 80 such an extent that the top bar would become detached from the wringer frame.

From the foregoing description, it will be seen that I have provided a pressure releasing device for a clothes wringer in which the pressure means can be instantaneously released by allowing the top bar to move vertically a sufficient distance to release the pressure means, the movement of said top bar being limited by the vertically disposed slots of the members carried by the side bars of the frame and prevented from being detached by the heads formed on the ends of the flat spring carried by said top bar whereby a pressure releasing device is provided which releases the pressure means without detaching the top bar from the wringer frame.

I claim:

1. A clothes wringer, comprising a frame having pressure rolls and pressure means mounted therein, a top bar for said frame having pressure screws for adjusting said pressure means, members secured to the side bars of said frame having substantially inverted T-shaped openings, a spring carried by the top bar of said frame co-operating with said openings, and means co-operating with said spring for allowing said top bar to move vertically within said frame. 100

2. A clothes wringer, comprising a frame having a vertically mounted top bar carrying pressure screws, members carried by the side bars of said frame provided with inverted T-shaped openings, a spring slidably carried by said top bar having substantially T-shaped ends co-operating with the openings for holding said top bar in position within said frame, and a member co-operating with said spring for moving the ends of said spring inwardly for allowing said top bar to move vertically within said frame. 115

3. A clothes wringer, comprising a frame having pressure rolls and pressure means mounted therein, a top bar for said frame having pressure screws for adjusting said pressure means, members secured to the side bars of said frame provided with horizontally disposed slots registering with the vertically disposed slots, a spring slidably car- 125

ried by said top bar having its ends seated within the horizontally disposed slots of said members, and provided with reduced portions adapted to enter the vertically dis-

posed slots, and means coöperating with said spring for moving the reduced portions of said spring into alinement with the vertically disposed slots for allowing said cross bar to move vertically within the wringer

frame.

4. A clothes wringer, comprising a frame having pressure rolls and pressure means for said rolls, a resilient member having means for normally holding said pressure means in predetermined position, and means coöperating with said resilient member for releasing said pressure means.

5. A clothes wringer, comprising a frame having pressure rolls and pressure means for said rolls, members carried by the side bars of said frame, a resilient member coöperating with said members for holding said pressure means in predetermined position, and means coöperating with said resilient member for releasing said pressure means.

6. A clothes wringer, comprising a frame having pressure rolls and pressure means mounted therein, a top bar for said frame having pressure screws for adjusting said pressure means, members secured to the side bars of said frame having horizontally disposed slots registering with the vertically disposed slots, a flat spring slidably mounted on the under face of said top bar having its ends seated within the horizontally disposed slots of said members, and provided with reduced portions adapted to enter the vertically disposed slots, and a movable member carried by the top bar engaging said spring for moving the reduced end portions of said spring into alinement with the vertically disposed slots for allowing said cross bar to move vertically within the wringer frame.

7. A clothes wringer, comprising a frame having pressure rolls and pressure means mounted therein, a top bar for said frame having pressure screws for adjusting said pressure means, members secured to the side bars of said frame, a flat spring carried by said top bar coöperating with said members for holding said top bar in predetermined position, and a movable member mounted within the top bar coöperating with said flat spring for allowing said top bar to move vertically within said frame.

8. A clothes wringer, comprising a frame having pressure rolls and pressure means mounted therein, a top bar for said frame having pressure screws for adjusting said pressure means, members secured to the side bars of said frame provided with substantially inverted T-shaped slots, a flat spring carried by the top bar having T-shaped ends

coöperating with said T-shaped slots for holding and releasing said top bar, and a movable member carried by the top bar for depressing said spring.

9. A clothes wringer having pressure rolls and pressure means mounted therein, a movably mounted top bar carrying pressure screws coöperating with said pressure means, members secured to the side bars of said frame provided with substantially inverted T-shaped slots, a spring carried by said top bar having substantially T-shaped ends coöperating with said T-shaped slots for holding and releasing said top bar, and a member movably mounted within said top bar coöperating with said spring for releasing said top bar.

10. A clothes wringer having pressure rolls and pressure means mounted therein, a movably mounted top bar carrying pressure screws coöperating with said pressure means, members secured to the side bars of said frame having substantially inverted T-shaped slots, a flat spring slidably mounted on the under face of said top bar having substantially T-shaped ends coöperating with the T-shaped slots of said members for holding and releasing said top bar, and a push button slidably mounted in said top bar adapted to engage said spring for drawing the ends of said spring inwardly for releasing said top bar.

11. A clothes wringer having pressure rolls and pressure means mounted therein, a movably mounted top bar carrying pressure screws coöperating with said pressure means, members secured to the side bars of said frame having substantially inverted T-shaped slots, a spring carried by said top bar having reduced end portions coöperating with the T-shaped slots of said members for holding and releasing said top bar, a push button disposed within said top bar having a nut engaging said spring for contracting said spring to move the reduced portions at the ends thereof into alinement with the stems of the T-shaped slots of said members for allowing said top bar to move vertically.

12. A clothes wringer, comprising a frame having pressure rolls and pressure means mounted therein, a top bar for said frame having pressure screws for adjusting said pressure means, members secured to the side bars of said frame provided with horizontally disposed slots registering with the vertically disposed slots, a spring slidably carried by the top bar having its ends seated within the horizontally disposed slots of said members, and provided with reduced portions adapted to enter the vertically disposed slots of said members, and a push button slidably mounted within said top bar having a nut coöperating with said spring for depressing said spring centrally to move the reduced portions thereof into alinement with

the vertically disposed slots of said members for allowing said cross bar to move vertically within said wringer frame.

13. A clothes wringer, comprising a frame having pressure rolls and pressure means for said rolls, a resilient member having means for normally holding said pressure means in predetermined position, and means for contracting said resilient member for releasing said pressure means.

14. A clothes wringer, comprising a frame having pressure rolls and pressure means for said rolls, a top bar movably mounted within said frame having pressure screws for adjusting said pressure means, a resilient member carried by said top bar, keepers carried by the side bars of said frame adapted to be engaged by said resilient member for holding said top bar in predetermined position within said frame, and a movable member mounted within said top bar coöperating

with said resilient member for moving said resilient member out of contact with said keepers.

15. A clothes wringer, comprising a frame having pressure rolls and pressure means mounted therein, a movably mounted top bar carrying pressure screws for adjusting said means, a resilient member for holding said top bar in predetermined position within said frame, means carried by said top bar for moving said resilient member in position to release said top bar, and means for limiting the upward movement of said top bar within said frame.

In testimony whereof I hereunto affix my signature in the presence of two witnesses.

JOHN F. HEMENWAY.
